CLAIM

The ornamental design for a vehicle front end, as shown and described.

DESCRIPTION

FIG. 1 is a front elevational view of a vehicle front end showing my new design;

FIG. 2 is a front perspective view thereof;

FIG. 3 is a left side elevational view thereof, the right side is a mirror image thereof; and,

FIG. 4 is a rear perspective view thereof.

The broken lines shown throughout drawings views are for illustrative purposes only and form no part of the claimed design.

1 Claim, 4 Drawing Sheets
